STAPLE EXTRACTOR

Filed June 30, 1950

UNITED STATES PATENT OFFICE

2,638,313

STAPLE EXTRACTOR

Herbert W. Marano, Brooklyn, N. Y., assignor to
 Wilson Jones Company, Chicago, Ill., a corpora-
 tion of Massachusetts

Application June 30, 1950, Serial No. 171,500

11 Claims. (Cl. 254—28)

1

The present invention relates generally to devices for removing driven or clinched staples, and also relates generally to a device for removing driven or clinched staples and straightening the bent-over legs thereof. The device of the present invention is primarily, but not necessarily, connected with staples having a center section and a leg section at each end thereof extended over at right angles to the center section, which legs are bendable and may be bent inwardly against the center section when in use, and the device of the present invention is designed to remove and release staples of such general description. While well applicable to the removal of staples and the like, as above described, the device of the present invention may have other and further applications, and is to be limited in its application only by the scope of the annexed claims.

Many devices have been contrived in the past to remove driven or clinched staples, these prior devices taking many and varied forms, some of relatively simple construction and operation, and others of quite complex nature. It is believed, however, that none thereof operates as does the device of the present invention, wherein the bent-over staple legs may be straightened, at least partially, during the removal thereof from the clinched material.

A main object of the present invention, therefore, is the provision of a device of the character described which not only unclinches driven staples but also substantially straightens the bent-over legs thereof, whereby the possibility of injury to the operator of the device is minimized in the handling thereof.

An associated main object of the present invention is the provision of a device of the character described having a fixed vertical component and a second component initially pivotal with respect to the first component and thereafter vertically shiftable with respect thereto, the swinging and shifting component releasing and removing the clinched or driven staple.

Another object of the present invention is the provision of a device of the character described having a fixed vertically extending leg and a second leg initially pivotal with respect to the first leg, and thereafter vertically shiftable with respect to said fixed leg.

Still another object of the present invention is the provision of a device of the character described comprising a pair of straight line telescoping members and a third member normally angled with respect to the first two members, movement of the first two members towards each

other causing the third member to swing into parallelism with the said two members and thereafter upwardly and into the uppermost portion thereof.

Still another object of the present invention is the provision of a device of the character described comprising a vertical leg component having a horizontal foot portion, a manually controllable cap component telescopically disposed over and about the leg, the cap being normally urged upwardly of the leg, a second leg component also provided with a foot portion at the base thereof extending at right angles inwardly toward the first foot portion, the second leg being normally angled with respect to the first leg, downwardly movement of the cap initially causing pivoting of the second leg towards the first, and vertically upward movement of the second leg with respect to and along the first leg thereafter.

Other and further objects of the present invention will, in part, be obvious from the following description of an illustration embodiment, in part specifically pointed out hereinafter, and in part apparent from the drawings forming a part of this specification.

In said drawings, illustrating one form of device, constructed according to and embodying the present invention,

Figure 1 is in part a vertical sectional view and in part a side elevational view, illustrating the device in its "at rest" position, ready for use and operation on a clinched staple;

Figure 2 is a similar view of the device in an intermediate stage of operation;

Figure 3 is a similar view of the device in its ultimate position;

Figure 4 is a vertical sectional view on the broken line 4—4 of Figure 1;

Figure 5 is a bottom plan view;

Figure 6 is a horizontal sectional view on the broken line 6—6 of Figure 1; and

Figure 7 is a perspective view of the device in its "at rest" position.

The device, indicated generally by reference numeral 10, includes a vertical leg component 12 of U-section, having a body wall 14, side walls 16, 16, and a horizontally and inwardly extended portion 18, at the bottom thereof. As seen in Figure 7, extension 18 is centrally notched at 20 to define a pair of spaced fingers 22, 22, one on each side of notch 20. Side walls 16, 16 are progressively narrowed downwardly towards extension 18, as indicated at 23, to provide a definite projection of fingers 22, 22 beyond the narrowed side walls at the bottom of leg 12.

An inverted hollow casing or cap 30 is provided, of rectangular section, and the leg component 12 disposed therewithin. Cap 30 comprises a rear wall 32, a pair of side walls 34, 34, a front wall 36 and a top 38, and is of width sufficient to receive leg 12 snugly therewithin but of depth slightly larger than is leg 12, in order to provide space within casing 30 for means to control the relative movement of casing 30 with respect to leg 12, as will be detailed below. Cap 30 is formed of a pair of complementary sections *a*, *b*, whose meeting edges are formed with interfitting dovetail locks 31, 31.

A lengthwise extending abutment 40 is provided, disposed and secured inside casing 30 on the rear wall 32 thereof, extending inwardly thereof and substantially occupying the space between wall 32 and leg 12. The top of leg 12 is extended over, outwardly, as at 42, and the leg 12 and abutment 40 are so relatively disposed and assembled that extension 42 overlies abutment 40, which serves as a stop to limit movement of leg 12 downwardly, in the one direction, the underside of top 38 limiting movement of leg 12 upwardly, in the other direction. Abutment 40 is permanently fixed on the inner surface of rear wall 30 by a plurality of inwardly lanced fingers 44, 44. Cap 30 and leg 12 are thus telescopically arranged for relative movement along a vertical line.

A pair of vertically extending slots 46, 46 are provided in side walls 16, 16, for reasons to be detailed below, said slots being located about midway of the length of leg 12. A cross-pin 48 is provided, extending across walls 16, 16 of leg 12 through the slots for reasons to be detailed below. Pin 48 is trapped within slots 46, 46 by the overlying side walls 34, 34 of cap casing 30. A central opening 50 is provided through rear wall 14, by a portion of the material of wall 14 being lanced inwardly to form a horizontally extending platform 52. It is to be noted that the lower edge of cap 30 normally overlies platform 52, see Figure 1.

A second leg 60 is provided, also U-shaped in section, opening towards the open aspect of leg 12. Leg 60 has a main wall 62, side walls 64, 64, and an inwardly directed centrally located extension 66 at the bottom thereof, said extension 66 being aligned with recess 20 in extension 18 of leg 12 so as to fit therewith. Side walls 64, 64 are also progressively narrowed downwardly towards extension 66, as indicated at 68, to provide a definite and clear projection of extension 66 beyond side walls 64, 64. The upper portion of main wall 62 is angled upwardly and inwardly, as at 70, terminating in a short portion 70 extending beyond walls 64, 64 substantially parallel to extension 66. A normally expanding coil spring 72 is disposed within cap 30 trapped between portion 68 of leg 60 and the underside of cap wall 38, spring 72 serving normally to maintain the parts in the position illustrated in Figures 1 and 7. Main wall 62 of leg 10 is bumped out, as at 74, for reasons to be explained below.

A pair of transversely aligned openings 76, 76 are punched through sides 64, 64 near the top thereof, adjacent main wall 62, and cross pin 48 threaded therethrough. Leg 60 is of such length that its upper and bent over portions 68, 70 extend into and are overlaid by the side walls of cap 30.

An arcuate slot 80 is formed through each wall 64, 64 of leg 60, curving upwardly slightly from a point level with platform 52. A cross pin 82 is keyed into said slots, and one end of an arcuate-

ly shaped draw lever 84 is fixed to the center of pin 82. The free end 85 of lever 84 passes through opening 50, curving upwardly in the space below abutment 40 between wall 32 of cap 30 and the main wall of leg 12.

In operating the device of the present invention, fingers 22, 22 are disposed immediately adjacent the staple S to be withdrawn. Cap 30 is pressed downwardly against the normal tensioning of spring 72, when the lower edge 37 of cap wall 36 is pushed downwardly to ride along the outer aspect of leg 62. Said leg 62 is pivoted, as above noted, to leg 12 about pin 48, and is normally maintained in the position of Figures 1 and 15 by expanding spring 72, with the plane of leg 62 angled outwardly from the plane of leg 12 and cap 30. The forward end 71 of extension 70 limits pivoting movement of leg 62 outwardly under the pressure of spring 72, and the point of 20 application of spring 72-pressure on extension 70 determines the direction of biasing of leg 62, pivoted as it is at a point spaced laterally of extension 70.

As cap edge 37 rides over bump 74, leg 62 will 25 be caused to pivot about pin 48 and swing inwardly towards leg 12, finger 66 passing under the staple's center section into recess 20 between fingers 22, 22 of extension 18, and simultaneously drawing fingers 22, 22 under the staple center, 30 as illustrated in Figure 2.

As the downward pressure on cap 30 is maintained and continued, abutment 40 is brought into contact with the free floating end 85 of draw lever 84, and pressing on same causes it to rotate about an imaginary point between the ends thereof, and ride on platform 52, to lift leg 60 by means of lever pin 82. The movement of said lever pin 82 is initially downward along the path of arcuate slots 80, 80 and thence upwardly, as 35 seen in Figure 3, pin 48 simultaneously riding upwardly in vertical slots 46, 46 in leg 12.

As staple S is withdrawn, its bent-over legs are straightened against the outer edges of fingers 22, 22, and the withdrawn staple is confined between finger 66 and the edge 23, 23 of side walls 16.

The device, with the exception of spring 72 and pins 48 and 82, may be formed as by stamping or otherwise of standard cold rolled steel, and may 50 be nickel plated, or otherwise surface coated, as desired to enhance its appearance. Assembly of the mechanism, as shown, is achieved without the use of screw fastenings. The components *a*, *b* of cap 30 may be shaped progressively in a die from flat sheet metal, and closed by dovetail locks 31, 31. The legs 12, 60 are connected as 55 described and locked into cap 30 by the abutment limit stop 40, which is permanently secured by lancings 44, 44.

Having now described the invention, what is 60 claimed and desired to be secured by Letters Patent is:

1. A staple extractor comprising a first staple engaging leg member and a second staple engaging leg member pivotally mounted on the first leg and normally swung away therefrom in non-operative relation thereto, a plunger disposed about the upper ends of the legs and operatively associated therewith for sliding movement downwardly along the length of the first leg, the second leg being reciprocably slidable within the plunger, initial downward movement of the plunger along the first leg engaging the second leg and pivoting said second leg into operative 65 relation to the first leg, further
2. A staple extractor comprising a first staple engaging leg member and a second staple engaging leg member pivotally mounted on the first leg and normally swung away therefrom in non-operative relation thereto, a plunger disposed about the upper ends of the legs and operatively associated therewith for sliding movement downwardly along the length of the first leg, the second leg being reciprocably slidable within the plunger, initial downward movement of the plunger along the first leg engaging the second leg and pivoting said second leg into operative 70 relation to the first leg, further
3. A staple extractor comprising a first staple engaging leg member and a second staple engaging leg member pivotally mounted on the first leg and normally swung away therefrom in non-operative relation thereto, a plunger disposed about the upper ends of the legs and operatively associated therewith for sliding movement downwardly along the length of the first leg, the second leg being reciprocably slidable within the plunger, initial downward movement of the plunger along the first leg engaging the second leg and pivoting said second leg into operative 75 relation to the first leg, further

downward movement of the plunger raising the second leg within the plunger.

2. A staple extractor as in claim 1, including means normally operable to urge the plunger upwardly of the legs, said means maintaining the second leg angularly of the first leg.

3. A staple extractor as in claim 1, including means within the plunger to limit relative lengthwise movement of the first leg with respect thereto in both directions.

4. A staple extractor as in claim 1, and spring means inside the plunger normally operable to urge the plunger upwardly of the legs, one end of the spring bearing against the underside of the plunger top and the other end of the spring bearing against the top of the second leg.

5. A staple extractor comprising a first and fixed leg member, a second and relatively movable leg member connected thereto, a longitudinally extending slot in said first leg and an arcuate slot across the second leg, a transverse opening in the second leg, a pin through said transverse opening in the second leg and through the longitudinal slot in the first leg, a second pin through the arcuate slot in the second leg, a lever having one end thereof fixed to said second pin and its other end free, a plunger overlying both legs and reciprocably movable with respect thereto, initial movement of the plunger downwardly of the first leg pivoting the second leg about the first pin, further movement of the plunger downwardly of and along the first leg engaging the free end of the lever shifting same downwardly with said plunger, raising the pin-connected end thereof and moving the second pin along the arcuate slot and shifting the first pin and second leg upwardly along the slot in the first leg.

6. A staple extractor comprising an elongated, inverted, hollow walled casing open at the bottom thereof, a first staple-engaging leg and a second staple engaging leg disposed within the casing for reciprocable movement therealong, means inside the casing and on a wall thereof spacing the first leg from said wall, and trapping both legs therewithin and limiting movement thereof outwardly of the casing, second leg being pivoted on the first leg, and longitudinally slidably along said first leg, and a lever having one end associated with the second leg and its other end freely disposed within the space between the leg and the wall, downward movement of the casing bringing the spacing means into engagement with the free end of the lever to slidably raise the second leg upwardly of and along the first leg.

7. A staple extractor comprising an elongated, inverted, hollow walled casing open at the bottom thereof, a first staple-engaging leg and a second staple engaging leg disposed within the casing for reciprocable movement therealong, means inside the casing and on a wall thereof spacing the first leg from said wall, and trapping both legs therewithin and limiting movement thereof outwardly of the casing, the second leg being pivoted off-center of and on the first leg, and biased normally to extend angularly out of the axis of the casing and first leg, a projection on the second leg, downward movement of the casing engaging and bearing against said projection to swing same into the axis of the casing.

8. A staple extractor comprising an elongated, inverted, hollow walled casing open at the bottom thereof, a first staple-engaging leg and a second staple engaging leg disposed within the casing for reciprocable movement therealong, means inside the casing and on a wall thereof spacing the first leg from said wall, and trapping both legs therewithin and limiting movement thereof outwardly of the casing, the second leg being pivoted off-center of and on the first leg, a normally expanding coil spring bearing against the top of the second leg oppositely off-center from its pivot point biasing said second leg to a position angled outwardly of the axis of the casing and of the first leg, lever means within the casing having an end thereof engaged with the second leg, a projection on the outer aspect of the second leg, initial downward movement of the casing engaging and overriding the projection and swinging said second leg into the axis of the casing, subsequently continued downward movement of the casing engaging the free end of the lever, raising the engaged end thereof, and thereby raising the second leg upwardly and along the first leg.

9. A staple extractor comprising an elongated, walled casing open at the bottom thereof, a first staple-engaging leg and a second staple-engaging leg, the upper portions of the legs being disposed within the casing for reciprocable movement

therealong, limit stop means inside the casing and on a wall thereof spacing the first leg from said wall, a projection from said first leg extending into said spacing limiting movement thereof out of the casing by abutment against the limit stop means, an opening through the first leg, a lever having one end thereof associated with the second leg and its other end extending through the opening in the first leg and into the space between said first leg and the casing wall, downward movement of the casing bringing the limit stop means into engagement with the free end of the lever, depressing same and raising its other end and the second leg upwardly of and along the first leg.

10. A device as in claim 9, wherein the second leg is shorter than the first leg and is pivotally connected thereto, and having a longitudinally extending slot in the first leg along which slot the pivot of the second leg rides during its upward movement and return.

11. A device as in claim 9, wherein the second leg is shorter than the first leg and is pin-pivotally connected thereto, and having a lengthwise extended slot in the first leg along which the pivot pin of the second leg rides during its upward movement and return, an arcuate slot across the second leg and a pin therein connected to the one end of the lever, the lever being curved and pivoting about a point between its ends on movement of the limit stop against its free end depressing the latter and moving the connected end and pin along the arcuate slot of the second leg, raising same upwardly of and along the first leg.
